CLAIM

The ornamental design of a canopy for a pick up truck bed, substantially as shown.

DESCRIPTION

FIG. 1 is a perspective view of the side and top of a canopy for a pick up truck bed showing my new design; FIG. 2 is a top plan view thereof;

FIG. 3 is a side elevational view thereof, it being understood that the broken lines are for illustrative purposes only;

FIG. 4 is a front elevational view thereof;

FIG. 5 is a back elevational view thereof;

FIG. 6 is a bottom plan view thereof.
